Specification for Design.

Patented Nov. 24, 1914.

Application filed July 16, 1914. Serial No. 851,410. Term of patent 14 years.

To all whom it may concern:

Be it known that I, GEORGE W. J. MURPHY, a subject of the King of Great Britain, residing in Merrimac, county of Essex, and State of Massachusetts, have invented a new, original, and ornamental Design for Curtain-Fasteners, of which the following is a specification, reference being had to the accompanying drawing, forming a part hereof.

In the drawing, Figure 1 is a side eleva-

tion of a curtain fastener showing my design; Fig. 2 an edge elevation thereof; and Fig. 3 a plan view.

I claim:

The ornamental design for a curtain fastener as shown.

GEORGE W. J. MURPHY.
